(57) **CLAIM**

The ornamental design for a puzzle-shaped eye shadow palette as shown and described.

DESCRIPTION

FIG. 1 is a front perspective view of a puzzle-shaped eye shadow palette showing our new design.

FIG. 2 is a front elevation view of the puzzle-shaped eye shadow palette of FIG. 1.

FIG. 3 is a rear elevation view of the puzzle-shaped eye shadow palette of FIG. 1.

FIG. 4 is a right side view of the puzzle-shaped eye shadow palette of FIG. 1.

FIG. 5 is a left side view of the puzzle-shaped eye shadow palette of FIG. 1.

FIG. 6 is a top view of the puzzle-shaped eye shadow palette of FIG. 1; and,

FIG. 7 is a bottom view of the puzzle-shaped eye shadow palette of FIG. 1.

The broken lines in the figures are for the purpose of illustrating portions of the puzzle-shaped eye shadow palette, which form no part of the claimed design.

1 Claim, 5 Drawing Sheets
